UNITED STATES PATENT OFFICE

JOHN E. PRACNY, OF WATERBURY, CONNECTICUT, ASSIGNOR TO THE E. J. MANVILLE MACHINE COMPANY, OF WATERBURY, CONNECTICUT, A CORPORATION OF CONNECTICUT

METAL HEADING MACHINE

Application filed May 27, 1931. Serial No. 540,225.

This invention relates to open die metal heading machines. In such machines as commonly constructed the dies are opened, wire is fed longitudinally in between the dies, the dies are closed on the wire and move transversely so as to cut off a blank and present it in heading position, a punch moves up and swages the projecting end of the blank and then withdraws, the dies are then retracted to feeding position and opened and the headed blank pushed longitudinally out by incoming wire. These machines are large, heavy and expensive, and they require a punch stroke which is longer than the length of the headed blank as the punch must be withdrawn sufficiently for the headed blank to be ejected longitudinally from the dies, which adds to the cost of the machine and lowers the output owing to the time required for the punch travel.

The object of the present invention is to provide headers of this class with means whereby they may be used for heading blanks which are longer than the travel of the punch, and thus allow longer blanks to be headed on machines originally designed for shorter blanks, and also admit of an increase of speed as the travel of the punch may be reduced.

In accomplishing the object, the machine is provided with means which effects a necessary control of the separation of the dies, and also means which co-operates therewith to ensure the ejection of the headed blanks transversely down between the dies to an opening in the die pocket, instead of pushing them longitudinally from the dies as is the usual way.

Only so much of a conventional machine is illustrated as is necessary to understand the application thereto of the present invention.

In the accompanying drawings Fig. 1 shows a plan of a machine frame with the die retarding and blank ejecting mechanisms applied thereto. Fig. 2 shows an elevation of the side of the machine frame on which the blank ejecting mechanisms are mounted. Fig. 3 shows an elevation of the side of the machine on which the die retarding mechanisms are mounted. Fig. 4 is a transverse section across the frame looking toward the

dies which are shown in closed position. Fig. 5 is a similar view with the dies in open position. Fig. 6 shows a section of the die cap and ejecting plate and the face of a die. Fig. 7 shows an end view of the opened dies and the ejecting plate. Fig. 8 shows an edge view of the ejecting plate, at the end of a die. Fig. 9 is an end view of the closed dies and the retaining pin. Fig. 10 is a horizontal section showing the die actuating mechanisms. Fig. 11 is a horizontal section through the dies, which are in heading position.

The dies 1 and 2, with the required filling blocks 3, are located in the die pocket 4 and are held down by a die cap 5 and from pulling out by the face plate 6, in the usual way.

The die 1 is connected by a yoke 7 with the head 8 of the plungers 9 that are moved in and out by the toggles 10 actuated by the slide 11 which is reciprocated by link and lever connections with cams or cranks on the main shaft 12, in the well-known manner.

The die 2 is normally pressed toward the die 1 by the head 13 of the plunger 14 under the thrust of the spring 15 secured to the side 75 of the frame. On the outer end of this die plunger 14 is a head 16 with a beveled face that is adapted to be engaged by the beveled end of a bolt 17 which is movably mounted in a bracket 18 fastened to the side of the machine frame. This bolt is connected by a link 19 to a lever 20 which is keyed to one end of a shaft 21 that is supported by brackets 22 on the under side of the frame. On the opposite end of this shaft 21 is a rocker arm 23 with a roll 24 which rides under a cam plate 25 secured to the bottom of the gate 26 which carries the punch 27. The gate is reciprocated in the usual manner in machines of this type. A spring 28, which extends along the 80 side of the frame, thrusts against the upper end of the lever 20 and causes the roll 24 to bear against the cam plate 25.

As the gate recedes after heading a blank, the cam plate 25 engaging the roll 24 turns 95 the shaft 21 and causes the lever 20 to withdraw the bolt 17 from engagement with the end of the die plunger 14. The plunger is then free to be moved inward by the spring 15 and cause the die 2 to follow the die 1 from 100

heading position to feed position. This mechanism prevents the die 2 from being pushed over by the spring 15 for a short period after the blank is headed and while the punch is receding and the die 1 is being retracted. In order to prevent the die 2 from following the die 1 during this period, as a result of suction or any other cause, pins 31 with tapered lower ends 32 are loosely mounted in the die cap 5 so that the lower tapered ends will engage the edge of the die 2. These pins are normally pressed down by springs 33 on the die cap. After the die 1 has been moved a short distance from the die 2 and the bolt 17 is withdrawn from the die plunger, the spring 15 on the outside of the frame forces the die 2 over against the die 1, the pins yielding to permit this.

On a bracket 34 on the side of the machine frame near the rear end, is a stud 35 with an angle lever 36 which at one end has a roll 37 that engages with a cam 38 on the main shaft 12. The stud 35 also has a lever 39 that is connected by a link 40 to an angle lever 41 which is fulcrumed on a stud 42 projecting upwardly from the gate cap 43. In the other end of this lever 41 is a vertically movable knuckle stud 44 which has a globular head 45 that is fitted in the upper end of a lever 46 mounted on a stud 47 projecting from the front face of the die cap 5.

The lower end of the lever 46 engages a stripper plate 48 that is movable vertically in a way in the face plate 6. The stripper is pressed downward by the action of a spring 49 tensioned between a lug 50 on the frame and the lever 41, and it is moved upward by the action of the cam 38 through the connections mentioned. The bottom edge of the stripper has a recess 51 with beveled sides shaped to engage and wedge a blank loose if it adheres to either of the dies, so the blank will drop through the opening 52 in the bottom of the die pocket.

The members of this mechanism are so timed that after a length of wire has been fed in between the dies both of the dies are moved together from feed position to heading position, and the blank cut from the wire is headed by the forward movement of the punch. As the punch is retracted the positive die 1 is withdrawn toward feed position, and for a short period while these movements are taking place the free die 2 is retained in heading position by the engagement of the retarding bolt with the die plunger. During this interval the ejector blade is moved downward for freeing the blank from the die cavities, if it has not already dropped. Then as the gate recedes further the cam on its underside causes the retarding latch to release the plunger so that the free die will be pushed over by its spring against the other die in feed position. With this means without lengthening out the frame of a machine or

increasing the punch stroke, which often in the past has been required for heading extra long blanks, long bolts may be rapidly headed.

The invention claimed is:

1. A metal heading machine of the character described having complementary dies movable transversely in a die pocket that has a discharge opening in its bottom wall, means for positively moving one die between feeding position and heading position, spring actuated means for moving the other die from heading position to feeding position, means for temporarily restraining the movement of the latter die for a short interval as the former die is being withdrawn from heading position, and means having a recess with beveled edges movable transversely of and across the ends of the die cavities during the interval said die is being restrained, for wedging free and releasing any blank that has adhered to either die.

2. A metal heading machine of the character described having complementary dies movable transversely in a die pocket that has a discharge opening in its bottom wall, means for positively moving one die between feeding position and heading position, spring actuated means for moving the other die from heading position to feeding position, means for temporarily restraining the movement of the latter die for a short interval as the former die is being withdrawn from heading position, and means movable in a channel across the ends of the dies transversely of the die cavities during the interval said die is being restrained, for releasing any blank that has adhered to either die.

3. A metal heading machine of the character described having complementary dies movable transversely in a die pocket that has a discharge opening in its bottom wall, toggle means for positively moving one die between feeding position and heading position, a spring actuated plunger for moving the other die from heading position to feeding position, a bolt for temporarily restraining the action of said plunger for a short interval as the former die is being withdrawn from heading position, and a plate movable in a channel vertically across the ends of the dies, transversely of the die cavities, during the interval said plunger is being restrained, for releasing any blank that has adhered to either side.

4. A metal heading machine of the character described having complementary dies movable transversely in a die pocket that has a discharge opening in its bottom wall, means for positively moving one die between feeding position and heading position, a spring for moving the other die from heading position to feeding position, means for temporarily restraining the action of said spring for a short interval as the former die

is being withdrawn from heading position, and means movable transversely of and across the ends of the die cavities during the interval said spring actuated die is being restrained, for releasing any blank that has adhered to either die.

5 5. A metal heading machine of the character described having complementary dies movable transversely in a die pocket that has a discharge opening in its bottom wall, means 10 for positively moving one die between feeding position and heading position, a spring for moving the other die from heading position to feeding position, means for temporarily restraining the action of said spring 15 for a short interval as the former die is being withdrawn from heading position, friction means retaining the spring actuated die from following the positively actuated die while the spring is restrained, and wedging means 20 movable vertically across the ends of the dies transversely of the die cavities during the interval said spring actuated die is being restrained, and adapted to engage the headed 25 end of any blank that has adhered to either die.
